9 Claims. (Cl. 121—38)

1

This invention relates to fluid pressure, particularly pneumatic pressure operated control systems, more particularly for use in aircraft.

It is common practice in hydraulic or pneumatic distant control systems provided to operate undercarriages, flaps, bomb doors and like apparatus on an aircraft, to provide a normal transmission line for carrying pressure fluid for normal operations and separately from this an emergency line which is capable of being operated when the normal transmission line is thrown out of action. In aircraft where the normal operation is effected by hydraulic or pneumatic means, the emergency operation generally comprises an accumulator storing gas under pressure with a supply line leading to the operating means, for example a jack.

The various arrangements embodying this construction which have hitherto been proposed are, however, subject to certain objections especially as regards the lowering of undercarriages in case of an emergency. When a double acting jack is used to operate an undercarriage, the pressure applied to one side of the piston has to force the fluid from the other side to the tank or exhaust, thus dissipating energy. This in practice will act as a sort of "cushion" on the action of the piston. If, on the other hand, the normal operation means have failed, the pressure in the jack cylinder is liable generally to be down to atmospheric pressure. If the pressure in the emergency line is then applied to the jack piston no resistance will be offered to its movement, so that the action of the jack may become too violent so that the piston is liable to damage due to impact or to be shorn off the piston rod.

One object of this invention is to provide an alternative operating system which when used in aircraft becomes an emergency operating system, that is to say an operating system which is brought into action when the normal operating system fails, and in which the above disadvantage is minimised.

According to one feature of the invention a pressure-operated control system comprises a supply of pressure fluid, a fluid motor such as a jack, means for placing the supply of pressure fluid in communication with both sides of the jack piston, the supply to one side of the differential piston being unrestricted, while the supply to the other side of the jack piston is restricted, and control means operable firstly by pressure in the unrestricted line to allow pressure to be built up in one side of the jack cylinder and subsequently by pressure in the restricted line automatically

2

to cut off supply of pressure fluid to the jack cylinder through the unrestricted line without interfering with supply of pressure fluid to the other side of the jack cylinder through the restricted line to operate the jack.

According to another feature of the invention the system comprises an alternative supply of pressure fluid capable of being placed in communication with both sides of the normal jack piston by an alternative operation valve, the alternative pressure fluid supply line to one side of the jack piston being unrestricted whilst the alternative pressure fluid supply line to the other side of the jack piston is restricted.

15 Control means may be provided which means are operable firstly by pressure in the unrestricted line to allow pressure to be built up in one side of the jack cylinder and subsequently by pressure in the restricted line to cut off supply of pressure fluid to the jack cylinder through the unrestricted line and allow supply of pressure fluid to the other side of the jack cylinder through the restricted line to operate the jack. Such control means preferably comprises a shuttle control 20 valve in communication with the alternative unrestricted supply line at one end and at the other end with the restricted line and in communication also with one side of the jack cylinder.

Two forms of the invention as applied to undercarriage equipment are diagrammatically illustrated in the accompanying drawings. Figure 1 shows the invention applied to a pressure operated system in which only a small effort is needed to lower the undercarriage, that is to say one in 35 which the emergency pressure acting on both sides of the jack piston as a differential jack piston is sufficient to lower the undercarriage. Figures 2 and 3 illustrate a more complicated form of system applied to a pneumatically operated control system for aircraft parts and in which it is necessary to apply a higher emergency pressure to one side of the jack piston in order to effect operation, for example the lowering of the undercarriage.

40 Referring to the arrangement shown in Figure 1, the normal control system includes the usual compressor or compressors with accessories producing pressure for normal operation, and any known locking means incorporated in the undercarriage and/or in the jack to maintain the undercarriage retracted when the normal operating system fails. None of these parts, however, are shown in the figure.

If the system is pneumatically operated the 45 gas, preferably air, is stored in an accumulator

having a connection 2 to, for example, an undercarriage selector 3. The said selector has two connections with the undercarriage operating jack, one line 4 leading to one side of the piston 7 to cause retraction of the undercarriage, and the other line 5 to the other side of the piston 7 to cause extension of the undercarriage, the selector being provided with an exhaust outlet 6. The jack 71 is of the double acting type and serves for the normal and emergency operation of the system, while the jack piston is a motor piston of the differential type, that is to say one effective area of the piston is larger than the other. In order to separate the normal system from the emergency system, the supply lines from the selector are led to the jack via two shuttle valves 8, 9.

The emergency system comprises an emergency accumulator 10 the supply of pressure fluid from which is controlled by an emergency operation valve 11 which connects the accumulator to a supply line 12 leading to the jack piston. This supply line is branched to provide an unrestricted supply line 13 to one side of the piston, whilst the other branch is restricted by a restrictor 14, thus providing a restricted supply line 15 to the other side of the jack cylinder, both the unrestricted and restricted supply lines communicating with the jack cylinder respectively through the shuttle valves 8, 9. The emergency operation valve 11 which is shown diagrammatically in the drawings is merely an alternately operable supply and exhaust valve of common, well known type. The chamber 33 is in communication with the accumulator 10 and contains air under pressure. The chamber 34 is in communication with the jack through the lines 12, 13 and 14. Extending through the chamber 34 is a valve stem 35 which carries an inlet valve 37 and an exhaust valve 38. The stem 35 may be moved by a handle or actuator 36 to cause closing of exhaust valve 38 and opening of valve 37, thus permitting pressure fluid to flow into line 12. Upon movement of the handle 36 in the other direction, inlet valve 37 closes, interrupting pressure fluid flow to the jack, and exhaust valve 38 may open, allowing the pressure fluid in chamber 34 and the supply lines 12, 13 and 14 to pass out to the atmosphere.

During the normal operation of the system to obtain retraction of the jack piston, pressure fluid supply from a compressor passes from the undercarriage selector 3 through the supply line 4 and actuates the shuttle valve 8 so that pressure fluid is admitted to the underside of the piston 7 in the jack cylinder, pressure fluid from the other side being exhausted through line 5 and exhaust 6; for extension of the jack piston, pressure fluid is admitted through line 5 and exhausted through line 4.

Should the normal operating system due to any cause be placed out of action, the resulting leak may ultimately lead to a drop of pressure in the said supply lines down to atmospheric pressure and in order to operate the jack it becomes necessary to operate the emergency supply system. In the case of it being desired to lower the undercarriage under emergency conditions, the emergency valve 11 is operated allowing the air stored under pressure in the emergency accumulator 10 to pass into the supply line 12. The pressure fluid will pass through the branch of the unrestricted line 13 into the shuttle valve 8, while the pressure fluid also passes through the restrictor 14 into the restricted supply line 15, but due to the restrictor 14 will cause the pres-

sure in the unrestricted line 13 to increase more rapidly than in the restricted line 15; thus the air under pressure in the unrestricted line 13 flows into the shuttle valve 8, thereby causing movement of its piston 81 so as to place the unrestricted line 13 into communication with one side of the jack cylinder, that is to say the side which normally is used for retraction of the jack piston. The pressure fluid passing through this shuttle valve 8 moves its piston 81 so as to isolate the connection between the shuttle valve and the jack cylinder from the normal working system; thus pressure is built up on the retraction side of the piston 7 in the jack. Air under pressure also passes through the line 15, in which the pressure builds up at a slower rate as a result of the restrictor 14, and through the shuttle valve 9 at the other side of the jack moving its piston 91 so as to allow pressure fluid to enter the jack cylinder 71 on the other side of the piston 7, causing therefore the jack piston 7 to move so as to lower the undercarriage, rapid movement of the piston being prevented due to the pressure being built up on the other side thereof.

It will be appreciated that when air under pressure is entering the emergency pipe lines from the accumulator 10, the restrictor 14 will not maintain the pressure on the full area of the piston 7 permanently lower, but only temporarily over a very short space of time, and as soon as the pressure on the full piston area is nearing the pressure of that on the underside of the piston 7, the jack 71 will extend and the air from the underside of the piston 7 will return into the emergency system which is a closed system with a substantially predetermined pressure; thus the pressure tends to equalise itself in this closed system, and the restrictor will only retard temporarily this tendency to supply pressure for one branch, thus producing the cushioning effect.

Referring now to the system shown in Figures 2 and 3 the normal operating system is the same and the jack 71 functions as a double acting jack serving for the normal and emergency operation of the system, the jack piston being either of the differential type or having two piston rods of equal diameters extending through the end walls of the cylinder. In the emergency circuit, however, there is provided the accumulator 10 and emergency control valve 11 which connects the accumulator to the supply line 12 branched to provide the unrestricted line 13 and the line 15 restricted by the restrictor 14. The line 13 is connected to one end of a shuttle control valve 16 and the line 15 is also branched as at 17 to communicate with the opposite end of the shuttle control valve 16. This valve is provided with two outlets, one 18 to exhaust and the other 19 to the jack 71. As in the previous arrangement the unrestricted and restricted supply lines 13, 15 communicate with the jack 71 respectively through the shuttle valves 8, 9.

The shuttle control valve 16 comprises a cylinder in which slides a piston rod 20, two pistons 21, 22, one at each end of the piston rod and two valve seats 23, 24 which allow one of the pistons to seat alternatively thereon.

During normal operation of the system, for retraction or extension of the jack piston, pressure fluid supplied through the supply lines 4 or 5, from the undercarriage selector 3, moves the shuttle valves 8 or 9, so that pressure fluid is admitted to one or the other side of the piston 7 in the jack cylinder 71. Should the normal operating system, due to any cause, be placed out

of action the resulting leak may ultimately lead to a drop of pressure in the said supply lines down to atmospheric pressure, and in order to operate the jack it becomes necessary to operate the emergency supply system. In the case of it being desired to lower, under emergency conditions, the undercarriage, the emergency valve 11 is operated allowing air stored under pressure in the accumulator 10 to pass through into the supply line 12. The pressure fluid will pass through the branch of the unrestricted line 13 into the shuttle control valve 16, while the pressure fluid also passes through the restrictor 14 into the restricted supply line 15, but as a result of the action of the restrictor the pressure in the unrestricted line 13 will increase more rapidly than in the restricted line 15; thus the air under pressure in the unrestricted line 13 flows into the shuttle control valve 16 thereby causing movement of the piston 22 so as to place the shuttle control valve into communication with the shuttle valve 8, that is to say the valve which is normally used for retraction of the jack piston. The pressure fluid passing through this valve 8 moves its piston 81 so as to isolate the connection between the valve 8 and jack 71 from the normal working system, so that pressure is built up on the retraction side of the piston 7 in the jack. Air under pressure also passes through the line 15, in which pressure is built up at a slower rate as a result of the action of the restrictor 14 through the shuttle valve 9 moving its piston 91 so as to allow pressure fluid to enter the cylinder 71 at the other side of the piston 7 causing, therefore, the jack piston 7 to move so as to lower the undercarriage, rapid movement of the piston being prevented due to the pressure being built up on the other side thereof. At the same time pressure fluid in the restricted line 15 passes through its branch 17 into the other end of the shuttle control valve cylinder 16 so as to move the piston 21, piston rod 20 and piston 22 back again in reverse direction cutting off the supply of pressure fluid to the jack through the unrestricted line 13 and allowing the shuttle control valve to open to exhaust at 18. Due to the provision of the restrictor 14 this return movement of the shuttle control valve 16 will only take place after sufficient pressure has been built up on the retraction side of the piston in the jack 71 so that substantially the full pressure of the emergency accumulator 10 can act on the jack piston 7 to lower the undercarriage. The pressure fluid on the other side of the jack piston 7 is forced through the shuttle valve 8 into the shuttle control valve 16 and from there to exhaust 18. Figure 3 shows the parts of the shuttle control valve 16 and shuttle valves 8 and 9 in their operative position when pressure fluid is fed from the accumulator 10 through the lines 13 and 15. As the pressure fluid from the retraction side of the jack piston is being exhausted through exhaust outlet 18 of the valve 16 after a predetermined pressure has been reached, a system incorporating the valve device 16 can be operated even if the jack piston has an equal area on both sides exposed to pressure so that the jack piston is non-differential.

As shown in Figures 2 and 3, the piston 22 may be biased by a spring 22a, its diameter being smaller than the diameter of the other piston 21, or any other known means to assist return may be provided.

Although the particular embodiment of the invention described above with reference to the

drawings is so described as applied to emergency operation, it is to be understood that the invention is also applicable in certain cases to normal operation of the jack in which case on operation of the jack, pressure fluid is admitted to both sides of the jack piston, there being provided control means operable firstly by pressure in the unrestricted line to allow pressure to be built up in one side of the jack cylinder, and subsequently by pressure in the restricted line automatically to cut off supply of pressure fluid to the jack cylinder through the unrestricted line, and allow supply of pressure fluid to the other side of the jack cylinder through the restricted line to operate the jack piston, whereby the fluid from the first side of the jack piston is exhausted.

What I claim is:

1. A pressure-operated control system comprising a supply of pressure fluid, a fluid motor including a cylinder and a differential piston therein, means for placing the supply of pressure fluid in communication with said cylinder on both sides of said piston including a supply line to the cylinder on one side of the piston which is unrestricted and a supply line to the cylinder on the other side of the piston which is restricted, and control means operable firstly by pressure in the unrestricted line to allow pressure to be built up in the cylinder on one side of the piston and subsequently operable by pressure in the restricted line automatically to cut off supply of pressure fluid through the unrestricted line to said cylinder on said one side of said piston and thereafter to establish communication between said cylinder on said one side of said piston and the atmosphere, thereby permitting exhaust of pressure fluid therein.
2. In a pressure-operated control system, a normal supply of pressure fluid, an alternative supply of pressure fluid, a fluid motor including a cylinder and a differential piston therein, means for placing the alternative supply of pressure fluid in communication with said cylinder on both sides of the piston, said means comprising an alternative operation valve, an unrestricted alternative pressure fluid supply line to the cylinder on one side of the piston, a restricted alternative pressure fluid supply line to the cylinder on the other side of the piston, and control means operable firstly by pressure in the unrestricted line to allow pressure to be built up in the cylinder on one side of the piston, and subsequently operable by pressure in the restricted line automatically to cut off supply of pressure fluid through the unrestricted line to said cylinder on said one side of said piston and thereafter to establish communication between said cylinder on said one side of said piston and the atmosphere, thereby permitting exhaust of pressure fluid therein, and valve means in each of said supply lines operable by pressure therein to prevent flow of pressure fluid from said normal supply to said cylinder.

3. A system as claimed in claim 2 in which the control means comprises a shuttle control valve mechanism in communication at one of its ends with the alternative unrestricted supply line and at the other one of its ends being in communication with the restricted supply line and in communication also with one side of said cylinder.

4. A system as claimed in claim 2 in which said valve means comprises a shuttle valve in said unrestricted supply line and a shuttle valve in said restricted supply line.

5. A system as claimed in claim 4 in which the said control means comprises a shuttle control valve in communication at one of its ends with the unrestricted supply line and in communication at the other of its ends with the restricted supply line and also with said cylinder.

6. A pressure-operated control system comprising a normal supply of pressure fluid, a fluid motor comprising a cylinder and a differential piston therein, and means for controllably supplying fluid under pressure to said motor for operating said piston including an alternative supply of pressure fluid, an operation valve for placing said alternative supply of pressure fluid in communication with both sides of said piston, a restricted alternative pressure fluid supply line leading from said operation valve to said cylinder on one side of said piston, an unrestricted alternative pressure fluid supply line leading from said operation valve to said cylinder on the other side of the piston, and valve means in each of said supply lines operable by pressure therein to prevent flow of pressure fluid from said normal supply to said cylinder.

7. A system as claimed in claim 6 in which said valve means comprises a shuttle valve interposed in said restricted supply line, and another shuttle valve interposed in said unrestricted supply line.

8. In a pressure-operated control system, a fluid motor including a cylinder and a differential piston, a normal supply of pressure fluid, a first supply line adapted to communicate with said cylinder on one side of said piston, a second supply line adapted to communicate with said cylinder on the other side of said piston, an exhaust, a selector valve mechanism for selectively placing one of said supply lines in communication with said normal supply and the other of said supply lines in communication with said exhaust, and vice versa, an auxiliary supply of pressure fluid, a third and relatively unrestricted pipe line adapted to communicate with said cylinder on said one side of said piston, a fourth and relatively restricted pipe line adapted to communicate with said cylinder on said other side of said piston, means for placing said third and fourth pipe lines jointly in communication with said auxiliary supply, and valve means re-

5
10
20

sponsive to pressure in said first or second pipe lines and the relative absence of pressure in said third and fourth pipe lines for establishing communication between said cylinder and said first or second pipe lines, according to which of said first and second pipe lines is pressurized, and responsive to pressure in said third and fourth pipe lines and the relative absence of pressure in said first and second pipe lines for establishing communication between said third and fourth pipe lines and said cylinder respectively on opposite sides of said piston.

9. In a pressure-operated control system, a normal supply of pressure fluid, an alternative supply of pressure fluid, a fluid motor including a cylinder and a piston therein, means for placing the alternative supply of pressure fluid in communication with said cylinder on both sides of the piston, said means comprising an alternative operation valve, an unrestricted alternative pressure fluid supply line to the cylinder on one side of the piston, a restricted alternative pressure fluid supply line to the cylinder on the other side of the piston, control means operable firstly by pressure in the unrestricted line to allow pressure to be built up in the cylinder on one side of the piston, and subsequently operable by pressure in the restricted line automatically to cut off supply of pressure fluid through the unrestricted line to said cylinder on said one side of said piston and thereafter to establish communication between said cylinder on said one side of said piston and the atmosphere, thereby permitting exhaust of pressure fluid therein, and valve means in each of said supply lines operable by pressure therein to prevent flow of pressure fluid from said normal supply to said cylinder.
